UNITED STATES PATENT OFFICE.

HELEN EBELL, OF LOS ANGELES, CALIFORNIA, ASSIGNOR TO BULLOCK'S, OF LOS ANGELES, CALIFORNIA, A CORPORATION OF CALIFORNIA.

DESIGN FOR WRAPPING PAPER.

Application filed January 7, 1927. Serial No. 20,304. Term of patent 3½ years.

To all whom it may concern:

Be it known that I, HELEN EBELL, a citizen of the United States, residing at Los Angeles, in the county of Los Angeles and State of California, have invented a new, original, and ornamental Design for Wrapping Paper, of which the following is a specification, reference being had to the accompanying drawing and forming part thereof.

The figure is a plan view of a fragment of wrapping paper, showing my new design.

The shade lines in the drawing do not represent any particular colors.

I claim:

The ornamental design for wrapping paper, as shown and described.

Signed at Los Angeles this 30th day of December 1926.

HELEN EBELL.
